UNITED STATES PATENT OFFICE.

OSWALD S. KUNKELY, OF NEW YORK, N. Y.

LABELING-MACHINE.

1,294,918.

Specification of Letters Patent. Patented Feb. 18, 1919.

Application filed July 15, 1918. Serial No. 244,994.

To all whom it may concern:

Be it known that I, OSWALD S. KUNKELY, a citizen of the United States, and a resident of the city of New York, borough of Bronx, 5 in the county of Bronx and State of New York, have invented a new and Improved Labeling-Machine, of which the following is a description.

My invention relates to a label-affixing 10 machine and more particularly to a machine for affixing labels to the opposite ends of a roll of ribbon or to the ends of a round box, carton, or the like.

General objects of the invention are to 15 provide a machine whereby ribbon rolls for example may be labeled speedily and economically with respect to the elements of time and labor. My improved machine is distinguished functionally and structurally 20 by various characteristics prominent among which are the following: The rolls are fed by an attendant to a guide track between two similar machine structures arranged to operate simultaneously to label the opposite 25 ends of the roll, and gravitate to a cradle which is intermittently given a kick-off motion to discharge the labeled roll; labels are gravitationally fed to chutes at opposite sides of the guide track from a supply con- 30 tained in a cylindrical label holder having a follower to advance the supply; the foremost label is detached by a revolving wiper to permit it to drop by its own weight to a position at rest at the bottom of the chute 35 in line with the roll in the cradle; the guide track accommodates two rolls superimposed on the one in the cradle and one of the superimposed rolls receives paste in spots from paste-applying devices which are given re- 40 ciprocatting rectilineal movement coaxial or substantially so with the roll to be pasted; the pasted roll is permitted by the successive discharge of the two preceding rolls to gravitate to the cradle and to be at rest 45 therein, and the cradle is held stationary while the label-applying devices are given rectilineal reciprocating movement to dis- 50 place the labels from the respective chutes and press them home onto the previously pasted ends of the roll.

The several individual main features outlined are coördinated in a manner to insure the proper sequence of the respective operations and the major devices characterizing 55 the machine, such for example as the label feed, wiper, paste device and label affixing

device, as will hereinafter appear, are constructed with a view not only to function with precision in the normal operation of the machine but with a view to the possible 60 contingency of such a temporary failure in the sequence of the operations as to offer an obstruction to the movement of a particular device in the general organism, whereby the obstructed device is permitted to yield should 65 the obstruction interfere with the normal movement thereof.

Specifically, means is provided to adjust the respective machine structures at opposite sides of the roll track to accord with a 70 roll or the like of particular dimensions, and also adjustments with a like object are provided for the kick-off cradle and other parts.

Reference is to be had to the accompanying drawings forming a part of this specification, it being understood that the drawings are merely illustrative of one example of the invention.

Figure 1 is a front elevation of a labeling machine embodying my invention; 80

Fig. 2 is a plan view thereof;

Fig. 3 is a longitudinal vertical section on an enlarged scale, through one-half of the machine as indicated by the line 3—3, Fig. 2; 85

Fig. 4 is a transverse vertical section on the line 4—4, Fig. 1;

Fig. 5 is a transverse vertical section of parts shown at the lower portion of Fig. 4, the view being given to show the position 90 of the cradle and its operating means in discharging a labeled roll;

Fig. 6 is a sectional plan view, the section being taken on the irregular line 6—6, Fig. 3. 95

Fig. 7 is an end elevation of the machine;

Fig. 8 is a partly sectional side elevation of a portion of the device for applying the label to the pasted roll in the cradle, a portion of the roll being shown and the label, 100 the holder thereof and a portion of the cradle being shown in section;

Fig. 9 is a view similar to Fig. 8 with the label affixing device in the position of displacing the label from the holder; 105

Fig. 10 is a view similar to Fig. 9 but with the label affixing device in the advance position occupied in pressing the label onto the roll;

Fig. 11 is a face view of the device for 110 applying the paste to the roll, parts being broken away.

In carrying out my invention in accordance with the illustrated example, a suitable frame 10 is provided, mounted on which are two similar machine structures 11, each with 5 its full complement of devices, said machines being adjustable to or from each other to accord with a roll or the like of a given length, there being shown for the purpose depending brackets 12 on structures 11-10 slidable on guide rods 13 supported at their ends in the frame 10. The structures 11 at their opposed ends present members forming jointly a trackway 14 to receive the ends of the rolls A, which latter are fed as by an attendant to said trackway. The trackway is continued downwardly to form a vertical drop 15 between the two machines to permit the foremost roll to finally rest in a cradle 16 composed of separate side members adjustable toward and from each other with the adjustment of the structures 11, the cradle being furthermore vertically adjustable as hereinafter explained to accord with a given diameter of the rolls, or other articles 25 being labeled. The cradle is mounted on a longitudinal rock shaft 17 and the upper portion thereof presents curved surfaces 18, the curves being struck from the center of the shaft 17 or approximately so to cause the 30 surfaces of the cradle to pass beneath the next uppermost roll and support the same as the lowermost labeled roll is discharged.

Label holders 19 are provided at the top of each machine structure 11 at opposite 35 sides of the trackway 14 and dip slightly toward the latter. The label holders 19 are cylindric to accord with round labels usually applied to rolls and the foremost label is detached by a revoluble device 20 that 40 intermittently wipes past the mass of labels in each holder to detach the foremost label. The wiping devices have a covering 21 of rubber as indicated in Fig. 3 and to coact therewith a friction device 22 is provided at 45 the forward end of each holder 19 at the under side to insure that the detaching wiper 20 will effectively engage the front label. The detached label drops to an inclined chute 23 presenting channeled side 50 members, the label finally coming to rest in a vertical receiver 24 constituting the lower terminal of the chute 23.

The label paste is applied to the ends of the roll and not to the label and for the 55 purpose a pasting device designated generally by the numeral 25 is given a rectilineal reciprocating movement in the manner hereinafter explained to deposit paste onto one roll in the drop 15 when the cradle 60 16 is at rest. In the arrangement illustrated two rolls A, as best seen in Figs. 3 and 4 are temporarily super-imposed and at rest on the roll which is at rest in the cradle. The roll thus pasted finally reaches the cradle by the successive discharge of the two

rolls in advance, and, timed with the pasted roll reaching the cradle, the label B previously arriving at the holder 24 is displaced and pressed home onto the pasted roll through the action of a presser head 26 hereinafter more particularly referred to, which has a rectilineal reciprocating movement as hereinafter explained. 70

The drive means include a drive shaft 27 here shown as having a pulley 28 to receive 75 power from a belt from any convenient source (not shown).

To rock the cradle 16 for discharging the labeled roll, use is made in the present instance of cams 29 on the drive shaft 27, each 80 cam acting against a friction roller 30 on a lever 31 fulcrumed as at 32 on the frame. Each lever 31 is pivotally connected at its lower end as at 33 with one end of a link 34, the opposite end of the link being pivotally 85 connected as at 35 with a rocker arm 36 on a hub 37 rigid on the cradle shaft 17 for rocking said cradle through the action of the cams 29 and the described connections. To limit the rocking movement of the cradle 90 use is made of stop arms 39 on the hub 37 adapted in the rocking of the shaft 17 to bring up against relatively fixed stop members here shown in the form of heads 40 on longitudinal adjustable rods 41 each having 95 a hand wheel 42 or the like and having a set nut 41^a, collar, or the like. The labeled roll, by the rocking of the cradle, is discharged into a chute 43. The said chute is secured in any suitable manner, the numeral 100 44 indicating a rod ranging longitudinally in the frame 10 between the ends of the latter to support the outer end of the chute.

The adjustment of the general structures 11 toward or from each other is effected in 105 the illustrated example as follows: Depending brackets 45 on each structure 11 have the heads 46 thereof bored and internally threaded to receive the right and left threads on a screw rod 47. Said screw rod 110 has suitable bearings in the frame 10 at the ends of the latter and is provided with a crank handle 48 or like means to turn it in either direction to cause the engagement with the heads 46 of the brackets 45 to move 115 the structures 11 oppositely, as desired, to give the track 14 and drop 15 a width to suit a particular length of roll. The shifting of the structures 11 is caused to correspondingly adjust the cradle by moving 120 the separate sides thereof toward or from each other, for which purpose in the form shown, shifting forks 49 are rigidly secured to the respective structures 11 in a position between shifting flanges or collars 50 on 125 heads 51 carrying respectively the sides of the cradle 16, said sleeves being slidable on the shaft 17. To provide for the vertical adjustment of the cradle 16 to suit rolls of a given diameter, so that the lowermost 130

roll, in the cradle 16, will align with the label-affixing head 26 and another roll will properly align with the paste device 21, use is made in the illustrated example of vertically movable bearing blocks 52 in which the shaft 17 turns, said blocks having movement in guides 53 in the frame 10 in response to the turning of vertical screws 54, having threaded engagement with the bearing blocks. Said screws are turned in any suitable manner, there being shown worm wheels 55 thereon meshing with worms 56 on a longitudinal shaft 57 provided with crank handles 58 or the like, said shaft turning in fixed bearings 59 in the frame 10.

Referring to the label feed a weight 60 is adapted to travel in each label holder 19 and advantageously has running wheels 61. The front of the weight is beveled and in front 20 of the same is a follower 63 inclined to the axis of the label holder so as to give the labels B an inclination as best seen in Fig. 3. A suitable handle 62 is provided and the holder is slotted lengthwise at the top to 25 accommodate the weight 60 and the said handle. The labels, the follower 63 and the weight 60 are passed into the holder from the rear end and fed toward the wiper or detaching device 20 under the pressure of 30 the weight 60 traveling down the inclined label holder.

The details of the friction device 22 are as follows: The same is generally in the form of a continuous rubber band which 35 passes about a cross bar 64 at the forward end of the label holder 19 at the bottom of the latter so that the label will be caught between said band and the rubber surface of the rotating device 20. Tension is supplied to the band 22 by a screw rod 65 turning in brackets 66 of the structure 11 and having a set nut 67. Said screw rod has a cross head 68 about which the band 22 passes. Thus, the band may be shifted on 45 said head for presenting a different wearing surface at the forward working end.

The label-detaching device 20 is secured to a transverse shaft 69 turning in bearings in the ends of a frame presenting side bars 50 70 slideable in fixed guide ears 71 and in order that said side bars may be shifted longitudinally to vary the position of the device 20 to properly engage a label, the rear ends of the side bars 70 are rigid with a cross bar 72, through which an adjusting screw 73 passes and is provided with a hand wheel 74 or the like for turning it. Said screw passes also through a rigid cross bar 76 of the structure 11 whereby the turning of the 55 screw will shift the side bars 70 and the shaft 69 and device 20. To drive the shaft 69 the same has a sprocket wheel 77 over which a belt 78 runs, said belt running also over sprocket wheels 79 on a transverse shaft 80 which is driven from the main 60

shaft 27 through the medium of intermeshing bevel wheels 81, 82. The belt 78 accommodates the slight adjustment necessary to be given the shaft 69. Each label holder 19 at the front end has a flange 84 extending laterally inward in front of the label at each side of the holder and set screws 84 engage these flanges and are adapted to be projected more or less against the labels and into the holder at each side of the latter, 75 the purpose being to insure that the front label will be held properly and in a necessary position for the detaching device 20 to be effective, and insure that the label will be relieved of the pressure exerted on the 80 inclined stack of labels after the detaching movement of the device 20 has taken place and insure also that the labels shall be properly dropped into the chute 23. It is to be observed that the label being very 85 light and depending solely on the action of gravity to reach the holder 24 at the lower end of the chute, its proper detachment and delivery in the plane of the chute becomes important and the wiper as well as 90 the screws 84 and the friction device 22, together with the form of the label holder and its label advancing weight 60, are designed to properly deliver the label to the chute, practice having demonstrated that 95 the described arrangement serves the purpose admirably.

Referring to the paste-applying device designated generally by the numeral 25, said device includes a paste box, the upper 100 end 85 of which is flaring or funnel-shaped and the lower end 86 thereof flattened and oblong. The paste box is adjustable in and detachable from a holder 87 carried by reciprocating rods 88. Set screws 89 in the 105 bottom of the holder 87 bear against the bottom of the paste box to give it vertical adjustment to conform the axis of the paste-applying head 90 with a given vertical adjustment of the cradle 16 to suit 110 rolls of a given diameter. The head 90 has outlet holes 90^a for the paste and it is flanged and threaded onto a boss 91 on the paste box. A disk valve 92 coaxial with the head 90 has paste outlets 93 out of register with the paste holders 90^a. Said disk valve 92 is carried by a pilot pin 94 adapted to have sliding axial movement in the paste head and paste box. A compression spring 95 is coiled about the pin 94 and the 120 front end of the spring bears against the valve 92 tending to force it forwardly against the inner surface of the head 90 while the rear end of the spring abuts against the back of the paste box. The 125 spring 95 normally maintains the disk valve 92 against the inner surface of the head 20 and thereby the pilot pin 94 will project beyond the head 90 to contact with the end of the roll A. As the rods 88 are moved 130

toward the roll A therefore, the pilot pin 94 will first contact with the roll. The continued advance of the rods 88 will cause the pilot pin to recede within the plane of the front surface of the head 90 and cause the said head to contact with the end of the roll, thereby depositing the paste in spots corresponding with the positions of the outlet holes 90^a. It will be understood 5 as the disk valve 92 recedes with the pilot pin, paste will pass forwardly through the holes 93 in said valve to the space between the valve and the head 90. Thus, as the rods 88 reverse the movement as herein- 10 15 after explained and carry the head 90 away from the roll A the reaction of the spring 95 presses the valve forwardly against the head 90 and forces the paste out through the holes 90^a ready to be deposited in spots 20 by the advance of said head against a roll. The rods 88 are part of the paste box carrier and have sliding guided movement in fixed bearings 96, 97 on the structure 11. Compression springs 98 are coiled about the 25 rods and bear at one end against the bearings 96 and at their other ends against set collars 99 for varying the tension of the springs. I provide means to actuate the carrying frame of the paste box in con- 30 sonance with the movements of the label-affixing head 26 to thereby insure proper sequence of their operations for which purpose a pendulous device is employed in the form advantageously of rods 100 pivoted at 35 their upper ends as at 101 and made rigid with a cross bar or girt 102, said pendulous device being adapted to be actuated directly with the movement of the presser head 26 which is positively actuated as hereinafter 40 explained, whereby the pendulous device is given an intermittent vibratory movement. A yieldable connection is established between the pendulous device 100 and the carrying frame of the paste box by the following means: A link 103 is pivoted at one 45 end as at 104 to the girt 102 and at its opposite end as at 105 with a pin or draw bar 106 which passes freely through a cross bar 107 rigid with the side rods 88. Said draw 50 bar 106 has coiled thereon a compression spring 108 and is threaded to receive a wing nut 109 or the like to vary the tension of said spring. The arrangement is such that as the pendulous device 100 is swung for- 55 wardly by the means hereinafter described, it will carry forwardly the girt 102 thereon and through the link 103, draw bar 106 and cross bar 107, the side rods 88 will be carried forwardly to advance the paste device 60 25 to apply the paste to the roll. The forward movement of the rods 88 will place the springs 98 under compression to return the paste device and its carrier. The power of the spring 108 in practice is superior to 65 that of the springs 98 and ordinarily said

spring 108 will not yield. If, however, the forward movement of the paste device or its carrier frame is obstructed then the pendulous device 100 with the girt 102, link 103 and draw bar 106 may respond to a forward 70 impulse given said pendulous device, the spring 108 yielding to the undue strain.

The label-affixing head 26 is positively driven, the transverse shafts 80 being utilized for the purpose. On each shaft 80 is a 75 cam 110 operating against a friction roller 111 on a slideable presser bar 112 carrying said head 26. A compression spring 113 is coiled about the presser bar 112, said spring 80 abutting at one end against a standard 11^a 80 through which the presser bar has guided movement, the opposite end of the spring bearing against a set collar 114 for varying the tension of the spring. In a second standard 11^b through which the presser head 112 85 passes is a pin 115 which is received in a longitudinal slot 116 in said presser bar, whereby to limit the retrograde movement of the presser bar under the reaction of the spring 113. The head 26 is carried by a 90 shank 117 which has sliding movement in an axial bore of the presser bar 112 and said bore receives a coil spring 118 tending to press the head 26 outwardly, the outward movement being limited by a pin 119 in the 95 standard 11^a, said pin being accommodated in a longitudinal slot 120 in the presser bar 112. A pilot pin 121 is seated against a spring 122 in an axial pocket in the shank 117, the spring tending normally to maintain the pilot pin projecting beyond the face of the head 26 (see Figs. 3 and 8 to 10). The head 26 is threaded onto the shank 117 and is held in adjusted position by a set nut 123. With the described arrangement when 100 a forward movement is imparted to the presser bar 112 by the cam 110, the spring 113 is compressed and the head 26 is advanced until the pilot pin 121 contacts with the label B which is at rest in the holder 24, 110 thereby displacing said label, pressing its central portion against the roll A in the cradle 16. With the continued advance of the head 26 the pilot pin 121 will recede within the plane of the head 26 and the latter will firmly press the label against the end of the roll as indicated in Figs. 3 and 10. The reaction of the spring 113 will retract the presser bar 112 and head 26 when 115 permitted to do so by the revolving of the cam 110. If any obstruction is offered to the normal forward movement of the head 26, the resistance of the spring 118 will be overcome, thereby preventing damage. Said spring 118 also insures proper contact of the label with the roll by always affording the desired degree of elasticity to the parts. From the foregoing it will be seen that the delivery of the labels from the feed means to the holder 24 and the delivery of the 120 125 130

25 rolls to the cradle from the feed track or table to which the rolls are supplied by the attendant, the gravity of the labels and rolls is utilized. Thus, aside from the detaching 30 of a label from the supply and the delivery of the rolls to the track table 14, the feed is by gravity and the movements of the paste device 25 and the label-affixing head 26 are made to accord with the gravitational placing 35 of the labels and rolls. Briefly, the operation is as follows: A supply of labels B having been deposited in the respective label holders 19 in front of the traveling weights 60 and a supply of rolls having 40 been fed to the table or track 14 and drop guideway 15, the turning of the main drive shaft 27 will, through the cross shafts 80 and belts 78, revolve the label-detaching devices 20 to cause each of the latter to have 45 a wiping movement over the front end of the labels to frictionally engage the front label, thereby detaching the latter and permitting it to drop under its own weight and in its own plane through the guide chute 23 until 50 it comes to rest in the holder 24, it being understood that the label-affixing head 26 at this time is in the retracted position shown in Fig. 8. In the meantime the supply of 55 rolls will fill the vertical drop or guideway 15, the lowermost roll being in the cradle 16 and there being two superposed rolls at rest above the one in the cradle. While the cradle is at rest also, one roll A will be disposed between and coaxial with the paste-applying heads 90. The rotation of the shaft 80 will cause the cams 110 to force the presser bars 112 forwardly to displace the labels from the respective holders 24 and press 60 said labels against the opposite ends of the roll in the cradle 16. As the presser bars 112 move forwardly they are caused to swing the pendulous devices 100, any suitable parts on the presser bars being utilized for engaging said pendulous devices. In the 65 form shown the rods forming each pendulous device lie in front of the transverse shaft or pin 124 on which the friction wheel 111 turns. The forward swinging of the pendulous devices 100 actuate the side bars 70 88 through the connections previously described, thereby carrying the paste device 25 forwardly to press the head 90 thereof against the adjacent roll A to deposit paste in spots on said roll. As each shaft 80 continues to turn, the cam 110 thereof permits the spring 113 to retract the head 26 and the reaction of the springs 98 retract the paste device 25. Following the pasting of one roll and the applying of the label to the previously pasted roll in the cradle 16 and the retraction of the head 26 and paste device 25, the continued turning of the drive shaft 27 gives a kick-off movement to the cradle 16 to discharge the labeled roll, said shaft 27 90 acting through the described connections

29-37 between said drive shaft and the cradle shaft 17.

I would state in conclusion that while the illustrated example constitutes a practical embodiment of my invention, I do not limit myself strictly to the mechanical details herein illustrated, since manifestly the same can be considerably varied without departure from the spirit of the invention as defined in the appended claims. 70

Having thus described my invention, I claim as new, and desire to secure by Letters Patent:

1. A labeling machine for rolls and the like, including a roll holder, a guideway 80 through which the rolls may move under their own weight to said holder, said guideway being adapted to temporarily accommodate rolls additional to the one in the holder, a roll-pasting device adjacent to said guideway and adapted to have rectilineal reciprocating movement relative to the guideway and transversely thereto, a label rest adjacent to and in register with said roll holder, a guideway through which a 85 label may drop under its own weight and in its own plane to said label rest, a label-affixing device adjacent to said label rest and adapted to have rectilineal reciprocating movement relatively to said label rest and 90 toward and from the said roll holder, means to intermittently cause the labeled roll to be discharged from said roll holder, and means for actuating in unison said roll-pasting device and said label-affixing device between 95 the intermittent discharging movements of the labeled rolls. 100

2. A labeling machine including a holder for the article to be labeled, a guideway through which the articles to be labeled may 105 move under their own weight to said holder, said guideway being adapted to temporarily accommodate articles additional to the one in the holder, a pasting device adjacent to said guideway and adapted to have rectilineal reciprocating movement relatively to the guideway and transversely thereto, to apply paste to one of the articles while at rest in the said guideway before arriving at 110 said holder, a label rest adjacent to said holder, a guideway through which a label may drop under its own weight and in its own plane to said label rest, a label-affixing device adjacent to said label rest and adapted to have rectilineal reciprocating movement relatively to said label rest and toward and from said holder, means to intermittently cause a labeled article to be discharged from said holder, and means to actuate said pasting device and said label-affixing device between the intermittent discharging of the labeled articles. 115

3. A labeling machine including a holder adapted to receive an article to be labeled, means to direct articles to said holder in 120

succession, label feed means, a label rest 5 distant from said feed means and adjacent to said holder, means to cause labels to be delivered in single succession from the feed means to said rest, means to apply paste to an article on the way to said holder, and means to displace a label from said rest and apply it to the pasted roll in the holder.

4. A labeling machine including structures 10 spaced from each other to form a passageway therebetween, track members on the respective structures forming a guideway over which the articles to be labeled may travel, said structures being bodily adjustable toward and from each other to vary 15 the width of the guideway, a holder to which said guideway leads, said holder being adapted to receive an article while being labeled, a paste device on each of said structures at opposite sides of the guideway to be 20 adjustable with said structures in varying the width of the guideway, a label rest on each structure, said holder being disposed between said label rests and said rests being 25 adjustable with said structures, said holder having separate side members movable toward and from each other with the adjustment of said structures to accord with a given width of a guideway, means on each 30 structure to simultaneously displace the labels from the label rests and apply them to the article on the holder, means to give rectilineal reciprocating movement to said label-applying means, means to give rectilineal reciprocating movement to the paste 35 device in unison with the label-applying means to apply paste to an article in the guideway and before said article reaches said holder, and means independent of said 40 structures to adjust said holder relatively to the reciprocating paths of the label-applying devices.

5. A labeling machine including a paste 45 device, label-applying means, a guideway along which the articles to be labeled may be caused to travel in a path past said paste device and label-applying means in succession, said paste device and label-applying means being adapted to have rectilineal reciprocating movement to and from the path 50 of movement of the article, means to position a label in front of said label-applying means, actuating means to cause the label-applying means to apply a positioned label 55 to an article in the guideway, and means to actuate the paste device from the label-applying means.

6. A labeling machine including a device 60 to apply paste to an article to be labeled, means to apply a label to a pasted article, means to positively actuate one of said means, means to actuate the other of said means from the one positively actuated, a guideway over which the articles may move 65 in a path past the paste-applying and label-

applying means in succession, and means to position a label between the label-applying means and said guideway.

7. In a labeling machine having a guideway for the articles to be labeled and in 70 which the articles are caused to intermittently advance; a paste device, means to give rectilineal reciprocating movement to the paste device transversely of the guideway to apply paste to an article in the latter, said paste device including a head to deposit the paste, said head having a paste outlet, a pilot pin normally projecting beyond said head to contact with the article and adapted to recede with the advance of 80 the head against the article, and a valve adapted to be actuated by said pin and controlling said outlet; together with means to apply a label to the pasted article.

8. In a labeling machine having a guideway for the travel of the articles to be labeled, a paste box, a carrier for said box adapted to have rectilineal reciprocating movement to and from said guideway to deposit paste onto an article presented thereto 90 in the guideway, a spring-pressed pilot pin normally projecting beyond said paste box and adapted to recede upon engaging the article to be pasted, and a valve controlling the outlet of paste from the box and subject 95 to a receding movement of the pilot pin; together with means to apply a label to the pasted article.

9. In a labeling machine, a paste box, a carrier for said box adapted to have rectilineal reciprocating movement toward and from the guideway, means to position in front of the paste box an article to receive paste, means to actuate said carrier, valve means to control the outflow of paste from 100 the paste box, and a spring-pressed pilot movable forwardly with the paste box and adapted to recede relatively to the paste box to permit the latter to engage the article, the receding of the pilot serving to actuate 110 said valve means; together with means to apply a label to the pasted article.

10. In a labeling machine, a paste device adapted to have rectilineal reciprocating movement, means to position an article in 115 front of the paste device, to receive paste from the latter, a frame carrying said paste device, means to actuate the frame in a forward direction, a spring to return the frame after a forward movement, said spring being 120 adapted to be placed under tension by said forward movement of the frame, and a second spring interposed between the frame and said actuating means, said second spring being superior to the first spring and adapted 125 to yield to undue resistance offered to the forward movement of the carrier frame; together with means to apply a label to the pasted article.

11. In a labeling machine, a presser head, 130

- a label rest in front of said head, means to position in front of said label rest the article to be labeled, means to cause a label to be positioned in said rest, means to give rectilinear reciprocating movement to said head, and a spring-pressed pilot pin normally projecting from said head and movable therewith through said rest toward the positioned article, said pin being adapted to recede 5 within the plane of the presser head upon engaging the positioned article.
12. In a labeling machine, a device to apply paste to the article to be labeled, a label-applying device, a label rest in front 15 of the label-applying device, means to cause articles to be labeled to be positioned in succession in front of the labeling device and the label rest, means to give rectilinear reciprocating movement to said label-applying device, a pendulous device connected with the paste device, and means to give a forward movement to the pendulous device by the forward movement of the label-applying device.
13. A labeling machine including a holder adapted to receive an article to be labeled, a guideway for the travel of the articles to said holder, a paste-applying device adapted to have rectilinear reciprocating movement relatively to said guideway to deposit paste on an article therein before the article reaches said holder, a label-applying device adapted to have rectilinear reciprocating movement relatively to said holder, and means to adjust said holder relatively to the rectilinear path of the label-applying device to accord with articles of a given size, said paste device including a paste-applying head, and means to adjust said head on said label-applying device and relatively to the rectilinear path of the latter to accord with a given adjustment of said holder and without varying the said rectilinear path of the paste device as a whole.
14. In a labeling machine, a guideway for the articles to be labeled, a holder adapted to receive a supply of separate labels, said holder being disposed transversely to said guideway, a label rest below said holder, a chute leading from the label holder to said rest, means at the upper end of said chute to feed the labels in single succession from the supply to said chute, a rockable cradle in front of the label rest, to which cradle 50 said guideway leads, a paste-supplying device at a side of said guideway adapted to deposit paste on an article before reaching the cradle, a label-applying device adjacent to the label rest and movable through the latter toward and from the cradle to displace a label from said rest and apply it to the article in the cradle, a drive shaft, means actuated by said drive shaft and actuating the cradle to intermittently rock the same for discharging the labeled article, and means 55 to actuate the paste device and label-applying device while the cradle is at rest.
15. In a labeling machine employing a device to apply paste to the articles to be labeled and employing means to apply labels to the pasted articles; a chute through which labels may drop to a position to be engaged by the label-applying means, an inclined holder adapted to receive a supply of separate labels, means to press the labels forwardly in said holder, the front end of said holder lying adjacent to the upper end of the chute, a revoluble label detaching device adapted to intermittently have a wiper movement past the front end of said holder 60 to detach the labels in succession to permit them to drop into said chute, and a friction device on the front end of the holder at the under side to afford a yielding resistance to the pressure exerted on the label by said 65 label-detaching device.
16. In a labeling machine, an inclined label holder adapted to receive a supply of separate labels, means to press said labels forwardly in the holder, elements projecting 70 forwardly into the holder at the front end thereof at each side adapted to bear endwise against the front label in the holder, said elements being adjustable to extend more or less into the holder, and means in front of 75 the holder to detach the labels from the supply in single succession from the supply in the holder; together with means to cause delivery of an article to be labeled, and means to apply the detached label to said article.
17. In a labeling machine, label-applying means and means to discharge a labeled article from the machine, said last-mentioned means including a cradle for said article, a rock shaft on which the cradle is mounted, bearings in which said rock shaft turns, means to adjust said bearings to vary the positions of the cradle and the label-applying means, a drive shaft, a lever subject to said drive shaft, and a link connection between 80 said lever and said rock shaft; said link connections being adapted to accommodate 85 themselves to an adjusting movement of said bearings.

OSWALD S. KUNKELY.
